WEAR-TESTING FABRIC AND OTHER MATERIALS

Edgar F. Hathaway, Wellesley, and Walter Bixby, Dorchester, Mass., assignors to Shawmut Engineering Company, Dorchester, Mass., a corporation of Massachusetts

Application November 30, 1937, Serial No. 177,376

19 Claims. (Cl. 73—51)

Our present invention relates to testing the wearing qualities of various sheet materials such as fabrics, webbing, floor coverings and others, by effecting wear on them analogous to that expected in actual use. In various respects the invention presents improvements over that of our copending application Serial No. 757,358 filed December 13, 1934, now Patent No. 2,100,332, and as to all common subject matter the present application is a continuation-in-part of said earlier application.

In the drawings illustrating by way of example certain embodiments of the invention,

Fig. 1 is an elevation of the upper portion of one form of the wear testing apparatus;

Fig. 2 is a similar view showing the immediately lower portion of the apparatus, including the support for the specimen, the wearing element and the wear measuring instrument, Fig. 2 being in effect a downward continuation of Fig. 1;

Fig. 3 is a vertical section, on a smaller scale of the lower portion of the apparatus, including the cabinet base and its movable mounting, the receiving end of the dust-collecting system, and showing the general arrangement of the operating and control mechanism;

Fig. 4 is a vertical section through the dust receptacle of Fig. 3;

Fig. 5 is a horizontal section on the line 5—5 of Fig. 11;

Fig. 6, on a similar scale as Figs. 1 and 2, is a plan of the specimen-holding platen and the releasable means for securing the specimen thereon;

Fig. 7 is an enlarged vertical section as on the line 7—7 of Fig. 6, with the clamping means in an intermediate position as during the installation or removal of a specimen;

Fig. 8 is a view similar to Fig. 7 but with the specimen fully installed;

Figs. 9 and 10 are fragmentary views corresponding to portions of Figs. 7 and 8 illustrating the securing of different types of test materials on the platen;

Fig. 11 is a vertical section on the lines 11—11 of Figs. 1 and 2;

Fig. 12 is a section corresponding to the upper portion of Fig. 11 but taken at right angles to the latter;

Fig. 13 is an enlarged vertical section through certain valve mechanism associated with the suction gauge;

Fig. 14 is a sectional view of the venting or bleeder valve;

Fig. 15 is a view of the mounting means for the electric contact finger of the stop mechanism;

Fig. 16 is a wiring diagram of the several electric circuits associated with the apparatus;

Figs. 17 to 21 inclusive are bottom plan views of various forms of wearer head or shoe for alternative use under different test conditions;

Figs. 22 and 23 respectively are a side elevation and a top plan of a thermostatic control associated with the wearer head;

Fig. 24 is a vertical section of a wearer head or shoe equipped fluid cooling means;

Fig. 25 is an enlarged vertical section through 15 the recorder drum and marking device;

Figs. 26, 27 and 28 are elevations of the wear measuring feeler, illustrating three different positions of adjustment, giving different charting ratios; and

Figs. 29 to 32 illustrate operating and control mechanism for the wear-measuring feeler, whereby the machine may be set to effect wear measurements at different times, wherein

Fig. 29 is a view partly in plan and partly in horizontal section taken as if looking down on the line 29—29 of Fig. 3, and on a larger scale,

Fig. 30 is a view, mainly in elevation, of the mechanism of Fig. 29 as seen from a position below said figure,

Fig. 31 shows a portion of the mechanism of Fig. 30, as if viewed from the right and in a vertical section along line 31—31 of said Fig. 30, and

Fig. 32 is an exploded view of a timing unit 35 seen in Figs. 29 to 31.

The apparatus as herein illustrated is of the same general design and arrangement as in said copending application. It includes a lower supporting portion comprising suitable framing and an enclosing cabinet 1, see particularly Fig. 3, in which the main operating parts are housed. As in the previous application the device as a whole may be set on wheels or castors for readily shifting it to various points of use. Supported on 40 the framing and closing in the top of the cabinet 1 is a table or platform 2, Fig. 2, on or about which the wearing, measuring and recording instrumentalities are disposed. It will be noted that Figs. 1 and 2 are views looking at the apparatus from one corner of the base portion.

The fabric or other specimen to be tested is secured flatwise on a platen or specimen-holder 3 above and substantially central of the platform 2 and supported for movement in its own 45 horizontal plane in a similar manner as in the

preceding application. In view of the full disclosure in said application it is sufficient for present purposes to note that the platen 3 as a whole receives a sinuous movement in a closed path, this movement being compounded of that of a crosshead which is movable on guides on the platform 2 in one and the reverse directions, and which in turn supports the platen for movement at right angles relatively to the crosshead. These relative movements and the total resulting compound movement of the platen are produced by cam mechanism in the base portion similarly as in the previous case.

In the present instance the platen or holder in its entirety comprises in addition to the block, anvil or platen proper 3 on which the specimen is placed, a relatively large, heavy, laterally extended base portion 4 to which the block or platen proper 3 is detachably secured as by screws 5 at its corner portions; see Fig. 6. This base portion 4 is of substantial thickness, particularly throughout its peripheral portions, as clearly seen in Fig. 2, so that it contains a considerable mass of the metal or other material of its composition and accordingly possesses a substantial inertia and is not readily subject to vibration. This heavy base portion of the specimen holder is symmetrically disposed relative to the platen 3 and is centrally apertured, and recessed at its under face to accommodate the operating connections such for example as illustrated in the earlier application.

As partially shown in Fig. 3, sufficiently for an understanding of the present invention, said connections include cam levers, one set of which is seen at 6, cooperating with cam tracks in the upper and lower faces of the platen cam 7 on a main vertical shaft 8. This shaft is driven by a worm gear 9 meshing with a worm on the same short shaft 10 with a large gear 11. The latter in turn is driven by a gear 12 coaxial with a pulley 13 driven by a belt connection 14 from the motor 15, by which all the moving parts are operated in the illustrated embodiment.

Considering now Figs. 2 and 6 to 10, improved means are herein provided for securing the test specimen on the platen 3. As seen in said figures, particularly Fig. 6, the platen is rectangular and is equipped with releasable clamping devices at each of its four sides. At each side the platen 3 has at its lower portion an inwardly extending slot 19 for the reception of a plate 20. On each plate 20 there is a cross piece or holder strip 21 secured to it as by screws 22. The plates 20 and their holder strips 21 at two adjacent or non-opposite sides of the platen are held in fixed position as by pins or screws 23 extending upwardly from the base portion 4 of the platen. The other two plates 20 are not so pinned, but are afforded a limited in-and-out sliding movement relative to the platen for a purpose to be described.

Each of the four holder strips 21 is longitudinally slotted at its outer side face, as seen at 24 in Figs. 7 and 8. This slot is adapted to receive the corresponding inturned edge of the test specimen S in the manner seen in said Figs. 7 and 8. These edge portions of the specimen are adapted to be securely clamped in their respective holder strips 21 by clamps or clamping slides 25, one paralleling each holder strip 21 and guided for sliding movement on the corresponding plate 20. The clamps 25 are adapted to be forced into holding engagement with the specimen as by means of the clamping levers 26, one 75

for each side of the platen 3 and each pivoted as at 27 on the corresponding plate 20. Each clamping lever has at its inner end a clamp camming portion 28 and a flattened locking portion 29. By swinging the clamping levers 26 in the clockwise direction as seen in Fig. 6 their cam portions force the clamping slides inwardly into specimen-holding position as in Figs. 7 and 8. In this position the specimen, generally a fabric of some sort, is firmly held along each edge portion, being tightly nipped between the upper wall of the slotted portion of the particular holder strip 21 and the upper corner portion of the corresponding clamp 25. The clamps preferably have their inner faces downwardly and outwardly inclined, as illustrated, to facilitate this clamping action. By moving the clamping levers through approximately 180° their flattened portions 29 engage the clamps, this locking the latter and the levers in clamping position.

Means desirably is also provided for stretching or holding the specimen under tension, in two directions, while it is on the platen 3. To this end, the plates 20 and their attached holder strips 21, at two non-opposite sides of the platen 3, those at the lower portion of Fig. 6, are permitted a limited in-and-out sliding movement as previously mentioned. At those sides the plates and holder strips are normally urged outwardly by one or more symmetrically disposed coil springs 30 received in recesses in the plate 3 and each bearing outwardly against a collar 31 on a stud 32. The inner end of each such stud extends centrally into and acts as a guide for the corresponding spring and its outer end is threaded into a hole tapped through the vertical wall of the adjacent holder strip 21. The outer ends of the studs are formed as headless screws, being slotted or otherwise formed for engagement by a screwdriver or the like inserted through the slotted portion of the holder strip, on removal of the corresponding clamp 25. By thus turning the studs 32 the tension of the springs 30 may be adjusted as desired, to regulate the tension under which a test specimen is held.

Outward movement of these spring-loaded plates 20 is limited by their outward engagement with clamp-spreader levers 35 pivoted on studs 36 removably threaded into the base portion 4 of the platen, opposite the outer ends of said two movable plates 20. At their ends near their pivots these spreader levers 35 each have plate-engaging cam portions 37 and a flattened holding portion 38. As shown in Fig. 6 the spreader levers 35 are in one released position, in which the springs are free to move the plates 20 and the holder strips 21 thereon outwardly, as also seen in Fig. 8. Thus a specimen previously clamped in the holder strip is then placed under tension.

To facilitate mounting and demounting a specimen, the spreader levers 35 are swung, in a counterclockwise direction as viewed in Fig. 6, to move the corresponding plate and holder strip inwardly to a position as in Fig. 7, compressing the springs 30, and allowing the corresponding clamps 25 to be backed away from and thus free the specimen, when the corresponding clamping levers 26 have been shifted to their unclamping positions. The reverse procedure is followed for spreading or separating the holder strips and the corresponding clamps, in connection with installing a specimen on the platen. It will be noted that the clamp-spreader levers 35 each have two released positions, namely, either as seen in Fig. 6 or in

a diametrically opposite position, while in their spring-compressing position they stand with their handles projecting outwardly, at right angles to said positions, as seen in Fig. 7.

The clamping mechanism as illustrated in Figs. 6, 7 and 8 is adapted to accommodate the heavier, thicker test specimens, such as carpets, rugs and like heavy pile or other fabric, or any comparatively thick, flexible sheet material to be tested, as indicated by the reference character S in said figures. For mounting materials of an intermediate thickness or bulk, such for example as plush fabrics for automobile interior and seat coverings, canvas, duck and various other materials of corresponding bulk, as represented at S', in Fig. 9, auxiliary clamping means may be provided such for example as shown in said figure. As there seen, each of the clamps 25 has removably secured to its top face a plate 40 of a width to extend inwardly beyond the front edge of the clamp and substantially into engagement with the vertical rear wall of the slotted portion 24 of the corresponding holder strip 21, in the holding position of the clamp 25, so as to engage and grasp the test specimen S' between the plate 25 and said wall. The specimen is also engaged and held between the upper face of the plate 40 and the top wall of the slotted portion of the holder and if desired a second plate 41 may be provided, or the plate 40 may be upwardly extended, to engage and grasp the fabric between such member 41 and the outer edge of the top wall of the slotted portion of the holder 21, as illustrated in said Fig. 9. These auxiliary clamping elements are removably secured to the clamps 25 as by screws 42.

For flexible sheet materials of a still thinner character, such for example as garment fabrics and various others, as represented at S² in Fig. 10, alternative clamping means may be provided in association with the platen 3, such for example as illustrated in said figure. As seen in each of Figs. 6 to 10, the specimen-receiving portion of the platen 3 is chamfered along its upper side edges, making the top portion of slightly reduced size. The vertical wall of this reduced portion, at each of the four sides of the platen, is formed with an inwardly extending slot 44 adapted to receive the horizontal flange of an L-shaped clamping strip 45. The down-turned edge portions of a relatively thin test specimen S², as seen in Fig. 10, are received between the vertical faces of the reduced portion of the platen and the vertical flanges of the clamping strips 45. The latter are removably held in clamping position as by the screws 46 tapped into the platen below the clamping strips 45 and having relatively large heads adapted to overlap the latter.

It will be seen that the specimen-holding platen or anvil is universally adapted for the holding reception of flexible test specimens of widely varying body of thickness, ranging for example from the heaviest of fabrics, such as long-pile Axminster carpets and other pile fabrics down to such relatively thin materials and fabrics as sheetings, shirtings and the like. The apparatus is also adapted for use in testing even thicker materials or stiffer or even non-flexible materials by securing them to the base portion 4 in place of the holding portion 3 of the platen or by fixing them to blocks similarly installed in place of said portion.

Returning to Figs. 1 and 2, there is provided above the main platform 2 an upper frame including a hollow pedestal 50 at one corner portion of the platform. Projecting inwardly from

the pedestal is a frame piece 51 having upper and lower arms 52, 53. The upper arm 52 together with an extension 54 thereof forms an arch spanning the specimen platen, diagonally of the platform 2. At its end opposite the pedestal 50 this arch is supported by a post 55 rising from the lower framing in the cabinet 1. As in the previous application, this upper frame serves to support the wear-producing mechanism and other associated parts to be described.

The wearing action on the test specimen is performed by a shoe 60, in cooperation with the moving platen, in a generally similar manner as in said earlier application, through the oscillation of the shoe while in pressing contact on the moving specimen, with or without an action of intermittent impact of the shoe upon the specimen.

The apparatus as herein illustrated embodies important improvements in the construction and arrangement of the wearer shoe and its supporting and operating parts. As seen in Figs. 2 and 11, the shoe 60, of circular form, has a neck 61 which is removably secured in a socket in the bottom of a shoe holder 70, as by one or more set screws 71. A dowel 72, Fig. 2, in the holder socket and receivable in a corresponding recess 62 in the shoe, see also Fig. 17, positively locks the shoe against turning in its holder.

Said shoe holder 70 is demountably held, as by set screws 73, at the lower end of the vertical tubular shoe-carrying shaft 75. This shaft, and consequently the shoe 60, is supported for rotary oscillation about its own axis and also for vertical reciprocation.

For this purpose the shaft 75, as best seen in Figs. 11 and 12, is slidably and rotatably received in a bushing 76 carried by the upper arm 52 of the top frame. This arm is hollow, providing within it a channel 77 communicating with the interior of the pedestal 50, for carrying off the worn particles or dust from the specimen being tested, the shoe 60 being centrally apertured at 63, as is also its holder 70, for upward travel of the dust through the shaft 75 to said dust channel 77. The shaft bushing 76 extends above the lower wall of said hollow arm 52 and into said channel 77. At its upper end is a cap 78 centrally apertured to support an open tube 79 extending down into the shaft 75 but spaced from it. The cap 78 and said tube are held against upward movement during the operation of the machine as by a retaining screw 80.

In Fig. 11 the shaft 75 and shoe 60 appear in their raised position, in which the top of the shaft comes substantially level with the inner face of the bottom wall of the arm 52 but is spaced below the cap 78. The vertical movement of the shaft and shoe, downwardly from their position of Fig. 11, and which at the most need be but slightly greater than the thickness of the given test specimen, is such that the shaft is never withdrawn below the bushing 76. The upward extension of the latter, together with the cap 78 and the tube 79, provides a chamber 81 above the shaft in open communication at all times with the interior of the shaft through the cylindrical space between the latter and the outer wall of the tube 79.

Heretofore difficulty has been experienced by reason of accumulation and caking of the worn particles or dust at the upper end of the shoe shaft. Despite the tightest packing the finely divided worn material, generally an extremely fine powder, would collect around and above the top of the shaft and interfere with its movement.

This difficulty has herein been overcome by the provision of said clearance chamber 81 and the additional provision of an air-entrance or cleaner passage 82, Fig. 12, drilled inwardly through the arm 52 and the bushing 76 so as to open into the chamber 81, communicating between the latter and atmosphere. By reason of the partial vacuum or negative pressure in the shaft 75 and dust channel 79 as maintained by their communication with the collecting end of the dust system, to be referred to, an inflow of air is set up through said cleaner passage 82, into the chamber 81 and thence downwardly about the tube 79 into the shaft 75. Thus any collection of dust at the upper end of the shaft is prevented and the latter is kept free of the objectionable accumulation mentioned.

As also seen in Figs. 11 and 12, means desirably is provided for taking samples of the worn-off particles or dust, in the course of or after a test, for use in studying the wearing action on the particular specimen. The arm 52 of the top frame, as in the preceding application, has an inspection and clean-out formation in its top wall, opening into the dust channel 77, above the shoe shaft 75, this opening being formed in a boss 83 on said arm 52. On this boss is an annular washer and closure-retaining ring 84 screwed or otherwise secured to it, as clearly seen in Fig. 12. The clean-out opening is closed by a removable cap 85 which conveniently may have a knurled knob 86 for manipulating it. The cap is firmly and removably held in seated position on said ring 84 as by a bottom-clamping member 87 secured to it as by a screw 88. Turning of the cap is adapted to engage the ends of said clamping member beneath circumferentially spaced inward projections 89 on the ring 84.

This closure cap 85 serves also as a support for the dust-sample collecting device above referred to. As seen in Figs. 11 and 12 said device comprises a small section 90 of wire screening or other perforate material the upper portion 91 of which is removably engaged beneath the head of the screw 88 on the cap. This sample-collecting screen is proportioned and arranged to extend downwardly into the path of the dust in the channel 77 of the arm 52. The screen is of less area than that of the dust channel, so as not to interfere with the action of the dust-collecting system. By merely removing the closure cap 85 worn particles or dust may be obtained for examination at any time. The screen 90 is readily removable, when its use is not desired, or it may be demounted and replaced by other similar specimen collectors, during the course of a test, if a number of dust samples are desired, the screens serving as convenient instruments for handling and studying them. In this connection screens having apertures of various different sizes may be employed, depending on the character of the test specimen.

Still referring particularly to Fig. 11, the shoe shaft 75 is guided, for rotation and vertical reciprocation, by a sleeve bearing 95, the upper end of which is fastened in a crosshead 96 having lateral trunnions 97 journalled in the shoe lifter arm 98, Fig. 1. This lifter arm is a double or forked element, the cross head 96 being received between its two parts, as clearly seen in Fig. 11. The shoe shaft 75 and said sleeve bearing 95 move up and down together, while the shaft is also given an oscillatory movement in said sleeve bearing and in the crosshead 96, the latter having a bushing 99 receiving the shaft. An anti-fric-

tion bearing 100 is provided above the crosshead and the sleeve 95 between said parts and a collar 101 fast on the shaft and through which the latter is oscillated.

5 The mechanism for so oscillating the shaft is similar to that of the previous application, including an arm 102, Fig. 11, projecting laterally from the collar 101 on the shaft and connected through a link 103, Fig. 1, to an arm (not shown) 10 on a collar 104, the connection between said arm of the collar 104 and the link being such as to allow up and down movement of the latter with the shaft 75. Said collar 104 is fixed at the upper end of a hollow shaft 105, Fig. 3, extending vertically through the hollow pedestal 50, similarly as in the previous application. Said hollow shaft 105 is oscillated by a pitman 105^a, Fig. 3, pivoted at one end, at the left in said figure, to a collar 105^b fast at the lower end of said shaft 20 and pivotally connected at its other end to a crank disk coaxial with the gear 12 and pulley 13 previously referred to.

The sleeve bearing 95 and the entire shoe operating assembly are further guided by the lower arm 53 of the top frame, through which said sleeve and the shaft 75 extend.

Referring again to Fig. 11, the shoe sleeve bearing 95 terminates at its lower end in an annular flanged foot 107 seating on another anti-friction bearing 108 supported on the shoe holder 70. A laterally projecting annular cup 109 may be provided below the bearing 108, held between it and the shoe holder, for catching any oil that might escape at the bearing or other point above it, and which might otherwise reach the shoe and the test specimen. Such protection is important because even a very small quantity of oil on the wearing face of the shoe or on the specimen is likely to introduce a factor of irregularity in the test.

40 As an additional safeguard in this connection we may provide a further drip plate or oil and dirt catcher, preferably below the cup 109 and adapted to receive possible overflow from the latter and to catch any other dirt or foreign matter which might otherwise fall onto the specimen being tested. As illustrated in Figs. 2, 5 and 11, this additional means comprises a two-piece glass or other plate 110, see particularly Fig. 5, straddling the shoe holder and apertured for passage of the latter. Each section of this plate is supported by a bolt 111 depending from a bracket 112 secured to the stationary lower arm 53 of the top frame, see Fig. 11, spacer sleeves 113 on the bolts serving to hold the plate sections firmly in their horizontal position. The two sections are adapted to be swung apart, about their supporting bolts 111, to give full access to the shoe and associated parts. They are held together in edge-wise abutting relation, as seen in Fig. 5, as by means of hook 114 on one section and engageable with a button 115 on the other. The plate sections are also recessed at their juncture line, as at 116, for passage of the wear-measuring feeler device to be described.

45 From the foregoing it will be seen that the shoe 60, its holder 70, the shoe shaft 75 and the bearing sleeve 95 and parts connected to the latter are adapted to be moved up and down by the action of the shoe lifter arm 98 to which they are connected through the crosshead 96. The shoe shaft 75, shoe holder 70 and the shoe 60 are also capable of rotary movement about the vertical axis of the shoe and shaft, but only these 50 main parts of the shoe operating assembly par-

ticipate in said rotary movement or oscillation. The bearing sleeve 85 does not oscillate, being held thereagainst by its connection with the cross-head 90, and the anti-friction bearings are located between the non-oscillatory parts and those which oscillate. This construction and arrangement facilitates the operation of the wearer unit and greatly reduces any vibration transmitted to the other parts of the apparatus, particularly during oscillation of the wearer shoe while it is down in pressing engagement on the test specimen.

The lifter arm 88 already referred to, for effecting the up and down movements of the shoe, is hung on the top frame member 51, being pivotally connected at one end, at the left in Fig. 1, as at 120, to vertical links 121, one at each side of the frame and pivoted thereon as at 122. At its other end said shoe lifter arm is pivotally connected as at 123 at the upper end of a lift rod 124 extending downwardly into the cabinet 1 and operated through mechanism therein which may be generally similar to that of the earlier application. Said mechanism is illustrated in Fig. 3 sufficiently for the purposes of the present application. Upward movement is imparted to said lift rod 124 by a horizontal cam lever 125 having its outer end pivotally connected to the lift rod, as at 126, and carrying at an intermediate point a roll 127 cooperating with an adjustable eccentric or cam 127^a on the shaft 10 previously referred to in connection with the drive for the platen. Said cam lever 125 is pivotally supported at its inner end as at 128 on a fixed cross piece 129 or other stationary part.

Downward thrusting action of the shoe and a continued pressing engagement thereof on the test specimen is effected by the dropping of the cam lever 125, the lift rod 124 and the lifter arm 88 when the roll 127 rides off from its cam 127^a. The force of this downward impacting and pressing action is determined by an adjustable weight 130 at the lower end of the lift rod 124, see Fig. 3. A stop 131 may be provided below the weight 130 to limit its downward movement and that of the shoe, to avoid damage to the platen or anvil 3 or to the shoe 60 by direct contact of said parts should a specimen be worn completely through.

Means desirably is provided for accurately controlling and adjusting the extent of vertical movement given to the shoe. For this purpose, referring now to the lower right portion of Fig. 2, the lift rod 124 has a threaded portion, above the platform 2, receiving a stop collar 132 engageable with the platform to limit down movement of said rod. Also on said threaded portion of the lift rod is a setting nut 133 the upper end of which is tapered and marked with a circumferential scale 134 for cooperation with a longitudinal scale 135 on the rod 124, as on a marker sleeve 136 thereon. The scales may be calibrated in small units of vertical adjustment in the up and down movement of the wearer shoe, whereby a micrometer setting for the latter is had. The scales 134, 135 may be arranged so that by setting their zero indications opposite each other either the upper or the lower limit of adjustment for the bottom position of the shoe is obtained. The two threaded members 132 and 133 cooperate and are manipulable in the manner of a nut and lock nut, each being moved in turn until the scale setting is as desired and the two parts are in abutting, mutually locking position.

As previously explained, and as in the earlier application, the worn particles of lint or dust are carried off from the test specimen as produced, passing up through the shoe 60 and its shaft 75 to the channel 77 in the upper arm 52 and which continues through the base or supporting frame element 51 into the pedestal 50. Referring now to Fig. 3, the dust is taken from the pedestal 50 through an outlet 140 at its lower portion, within the cabinet 1, and through a conduit 141 communicating between said outlet and a vacuum tank 142 mounted in the cabinet. In the tank is a dust receptacle or bag 143 detachably hung on a removable cover plate 144 for the tank, the cover plate having an inlet 145 for the dust and at which the lower end of the conduit 141 is connected. The bag 143 is of paper, fabric or other material of sufficiently porous character to allow air to pass through it but while retaining the dust particles, similarly as in known vacuum cleaners.

The negative pressure or partial vacuum in the dust-collecting system is maintained by a pump 146, Fig. 3, driven through a belt or other connection 147 with the motor. The intake side 25 of the pump is connected through piping 148 with the outlet 149 of the vacuum tank, while the outlet or pressure side of the pump discharges through a pipe 150 opening to atmosphere at 151. A considerable vacuum or negative pressure is found desirable, generally somewhere between 15 and 30 inches (column of water), depending somewhat on the character of the test material, and the pump employed is of corresponding capacity, that illustrated being of a rotary type operating with oil. Since a given test may be continuous over a period of several days, during which the pump operates continuously, it is important that its bearings receive constant lubrication, particularly if they are not of a ball-bearing or other anti-friction type. Accordingly, as seen in Fig. 3, an air reservoir or cup 152 may be provided, adapted to supply both the operating mechanism of the pump and its bearings. Oil is distributed from the cup 152 through a feed line 153 having branches, one of which is indicated at 154, leading to the bearings at the opposite ends of the pump shaft, and a branch 155 leading to the interior of the pump, through the intake piping 148. Oil from the cup 152 is forced up through a tube 156 and discharged above the upper end of the feed line. Air pressure is availed of for so upwardly forcing the oil, air being taken from the pipe 150 at the pressure side of the pump through a connection 157 extending into the cup 152 and communicating with an air pressure tube 158 having a reduced portion which opens upwardly into the lower end of the oil tube 156, whereby the air pressure forces the oil upwardly through said tube 156 from the supply in the cup 152.

In view of the importance of maintaining a substantially uniform negative pressure in the dust-collecting system, as appropriate for the particular test material, means desirably is provided for readily determining the pressure at any time and also for relieving it if necessary. Accordingly, there is herein illustrated a vacuum or negative pressure gauge 160, Figs. 1 and 13, graduated to read in inches of water. The gauge is adapted to be placed in communication with the channel 77 in the upper arm 52 through a coupling 161 threaded into an appropriate aperture in a wall of said arm, see particularly Fig.

13. It will be understood that the suction or negative pressure pulsates with the movement of the shoe, between a maximum at the times when the shoe is firmly engaged on the specimen and so restricting the entrance of air through the shoe, and a minimum when the shoe is lifted and the passage through it is accordingly wholly open. Hence if the gauge were always in communication with the air channel its indicator would pulsate correspondingly. To avoid this the gauge is so arranged that normally it is shut off, but may readily be caused to operate whenever a reading is desired.

Referring to Fig. 13, a control valve is accordingly provided for the gauge, including a valve housing 162 threaded into a laterally extending chamber 163 in the coupling 161. The latter has offset longitudinal passages 164 and 165, the lower passage 164 communicating between said chamber and the air channel 77 of the arm 52, and the upper passage 165 leading from said chamber to an upper chamber 166 into which the gauge stem 167 opens. At the inner end of the housing 162 is a seat 168 for a valve 169 on a stem 170 slidable in the housing and extending out through suitable packing 171 to an operating button 172. A spring 170^a between the packing and said button normally urges the valve outwardly into closed position on its seat. In Fig. 13 the valve is shown open, as if the button were being held in by the observer's finger. In this position the gauge is in communication with the suction system, through its stem 167, the upper chamber 166 and passage 165, and through an annular passage 173 opening into the valve housing behind the valve, thence through the valve opening and the lower passage 164 into the air channel 77. Normally during operation of the apparatus the valve accordingly stands closed and the gauge indicator remains at rest, at the zero end of its scale. To obtain a reading, however, it is necessary merely to press in the valve button 172, the valve again automatically closing when the reading has been made and the button released.

To relieve the negative pressure in the system or to prevent its passing a desired maximum, a venting or bleeder valve 175 may be provided at a convenient point, for example, adjacent the gauge 160, as seen in Fig. 1. Referring to Fig. 14, this valve comprises a plug or stem 176 threaded through a boss 177 on the wall of the upper arm 52 of the top frame. The inner portion of the plug has a beveled or inwardly deepening slotted formation 178 so that by turning the valve in or out the vent provided by said formation may be closed completely or opened to various sizes. A coil spring 179 surrounding the valve stem, between the boss 177 and the head or adjusting button at the outer end of the valve, urges it outwardly, taking up any play between the threaded member and the supporting wall of the arm 52 and so tending to hold the valve in any given position and against unintentional shifting.

In testing materials as herein contemplated it is generally important that the wearing action on different specimens which are to be compared shall be as nearly absolutely uniform as possible. The character and construction of the wearing surface for the shoe 60 therefore is a prime consideration, and much experimental work has been done in determining the most effective arrangements for the purpose. With said uniformity of action in view we employ in most in-

stances a wearing surface the main area of which is flat, hard and extremely smooth, avoiding surface irregularities which might produce a different abrading action at different times. In this connection our testing system also contemplates that there shall be one master or standard machine which may be used as a norm for establishing standards as to the wearing qualities of the various materials. Such machine is kept at some test headquarters, carefully guarded against being tampered with, and in a special room or other location where it may be operated under controlled standard conditions as to atmospheric temperature, relative humidity, cleanliness and others. Comparable results with other similar machines necessitate that the wearing instrumentalities be as nearly as possible identical, and such identity is best obtained in the use of a flat, smooth, hard wearing surface, as above mentioned. Ordinary abrasive surface means, such for example as generally used in grinder wheels, even wherein the surface is composed of minute granules or crystals, lack the desired uniformity of action, due largely to the surface irregularities, even though small, and to the wearing off of particles of the surface material which work into the test specimen and introduce uncertainty and nonuniformity of action.

Referring in this connection to Figs. 2, 11, and 30 to 24 inclusive, the wearer or shoe unit 60 comprises a wearing surface member or means 64 which as shown is made detachable from the foot and is cemented or otherwise secured in a shallow socket therein. As stated, this wearing 35 surface element is extremely hard and smooth, having a mirror finish. One of the best materials we have found for the purpose is that known commercially as "Norbide," having a hardness approaching that of diamond. Another material 40 successfully employed is glass, polished to a mirror finish. With some test specimens we have satisfactorily used a very hard steel, such for example as "Colonial .795" quenched in oil from 1900° F. soaked till cold and drawn to 400°. 45 When steel is used the shoe body 60 and the surface means 64 may be integrally formed or otherwise, while with "Norbide," or with glass or in any instance the detachable construction may be preferable, for reasons of economy and of re- 50 placement.

While the main area of the wearing surface of the shoe is flat and highly polished one or more channels or grooves desirably are formed in it, the number and arrangement of which may be 55 widely varied, for use with different test materials. Obviously some materials wear faster than others, so that a shoe suitable as the standard instrument for one class or type of material may wear a different character of material at too 60 rapid or too slow a rate for testing purposes. With the same test material the rate of wear, other factors such as the force and rapidity of impact and the rate of oscillation remaining the same, depends mainly on the wearing surface 65 channeling. In general, the rate of wear increases with an increased number of lineal interruptions of the surface, with the increased number of subdivisions of the surface, the smaller such subdivisions, the greater the wearing rate. 70 The directional arrangement of the lines and the accompanying configuration of the subdivisions also is an important factor. Another factor is the relation of the channeling to the central aperture 63 and to the periphery of the shoe, and we herein illustrate various shoe surface forma-

tions in which the channels provide air passages from the edge to the center, from edge to edge, between two intermediate points without communicating either with the edge or the center, or between an intermediate point and either the edge or the center, all having a somewhat differing action, due partly to the nature of the contact with the specimen and partly to the air-cooling and the dust-conveying effect of the channels in cooperation with the central aperture communicating with the vacuum system.

One construction and arrangement of the surface channelling is shown in Fig. 17, being the same as in Figs. 2 and 11. In this instance the channels 65 are radial and extend from edge to center, each providing an air passage communicating from the side face of the shoe to the central aperture 63, eight such radial channels 65 being illustrated in this instance, equally spaced. Thus when the shoe is down in pressing contact on the specimen air may enter the system through the channels, maintaining a dust-collecting flow and cooling the shoe. A greater or less number of the symmetrically disposed radial channels may be provided. This shoe, having its wearing surface of the materials as previously referred to, is particularly adapted for use in wear testing Axminster rugs and carpets, and other fairly heavy pile fabrics, as well as various other materials.

Fig. 18 shows the wearing face of a shoe in which the channels 66 are spirally disposed and extend from the edge to the central aperture 63, each through one convolution. Three such spiral grooves or channels are illustrated, starting at equally spaced points at the shoe edge and ending likewise at equi-spaced points about the central aperture, the two ends of each channel 66 being substantially opposite each other radially. In this form the cooling and dust-collecting effect is particularly efficient, adapting it for dense materials and others with which there is considerable heat generated in the wearing action.

In the shoe form of Fig. 19, the channels 67 are rectilinear and in a lattice arrangement, including two perpendicular diameters with parallel chords equally spaced at each side thereof. This construction includes edge to center communication as well as edge to edge passages. As in the other examples, increase in the number of channels and subdivisions of the wearing surface increases the rate of wear. For some of the durable materials such as linoleum, and fibre, cellulosic and other compositions, the squares or subdivisions of this lattice form, or the various subdivisions of the other forms, may be relatively small even approaching in width that of the channels themselves.

In Figs. 20 and 21 two further forms are illustrated, wherein the channels 68 and 69 respectively are closed, along continuous paths, having neither center nor edge communication. In Fig. 20 the channels are chordal, ending short of the periphery, and forming a rectangle, while in Fig. 21 they are concentric. Additional channels may be provided in the form of Fig. 20, while in Fig. 21 the number of channels, of which three are shown, may be made greater or less.

In said Figs. 20 and 21, wherein the channels do not lead to the central aperture 63, additional provision for air-cooling may be made as by means of one or more passages 68^a and 69^a respectively formed in the shoe above the wearing face and leading into the center aperture from

the side face of the shoe. These serve to maintain an air flow through the body of the shoe adjacent or in the wearing surface element, carrying off heat through the vacuum system. Similar channels may be provided in any other of the shoe forms if desired, as indicated at 68^a in Fig. 11.

Desirably means is provided for automatically stopping the machine in case the wearer shoe reaches a predetermined heated condition at which it is preferred to interrupt the test. Such condition is of infrequent occurrence sometimes arising in the testing of extremely durable materials, and the means referred to may be of a readily demountable or may be rendered inoperative when its use is not desired, or it may be employed as a precautioning measure at any time.

For this purpose, referring to Figs. 22 and 23, the shoe 60, or as there shown the shoe holder 10 included in the unit is equipped with a thermally responsive device 70^a illustrated as a bi-metallic element partly encircling the holder adjacent the shoe and attached as by a screw which serves also to ground said element onto the machine. At the determined critical temperature the straightening of the thermal element 70^a brings it into electrical contact with a point 70^b on a contact arm 70^c attached to a convenient stationary part, such as the lower arm 53 of the arch or top frame, and insulated from it. Through appropriate wiring connection, as will be referred to in connection with the wiring diagram, closing of a circuit at the thermal element acts to open the motor circuit and stop the apparatus.

In the testing of some materials, in which higher temperature conditions at the wearer head or shoe are to be expected, in the absence of some provision to the contrary, additional cooling for the shoe may be supplied. In Fig. 24 one form of such cooling means is illustrated, in which the shoe holder 70A is cored as at 74 to provide a circulating chamber for water or other fluid, an inlet and an outlet for which is indicated at 74^a and 74^b respectively. A rubber or other flexible hose 74^c connects the inlet 74^a with a water or fluid supply, while a similar connection 74^d leads from the outlet 74^b to waste or to a cooling and recirculating system. The hose connections are such and are so supported, as on the top frame, as not to interfere with the motions of the shoe.

Improved means coordinated with the wearing mechanism is provided for periodically measuring the depth of wear and charting a record of the same. Referring to Figs. 1 to 3, 25 and 29 to 31 a recorder drum 180 is demountably fixed as by a thumb nut 181 at the upper end of a vertical, rotary drum-operating or recorder shaft 182. This shaft is supported and journaled in upper and lower bearings 183, 183^a and extends vertically through the shoe-oscillating shaft 105 in the pedestal 50. It is driven in accurately timed relation with the wearing mechanism, including both the specimen platen and the wearer shoe, by a worm wheel 184 at its lower end and meshing with a worm 185 fast on a horizontal shaft 275 to be more fully described; see particularly Figs. 29 to 31. It is sufficient here to note that said shaft 275 is driven at selective speeds through a clutch-controlled change-speed gearing, to be referred to later and which receives its drive from a worm gear 186 turning on a bearing bushing 186^a in a bearing 186^b on a bracket

189 depending from the cross member 129. Said worm gear 186 is driven by a worm 187 fast on a lower horizontal shaft 188 rotatable in another bearing 188^a on said bracket 189. The inner end portion of said lower horizontal shaft 188 receives further bearing support in a vertical bracket 188^b on the stationary framing and has at its end a bevel pinion 190 meshing with a like pinion 191 at the lower end of the main vertical shaft 8 for the platen cams.

As seen in Fig. 1 and in detail on a larger scale in Fig. 25 the recorder drum 180 is adapted to receive a paper or other chart or sheet 192 on which the record is to be made. A typical form of chart is illustrated in the earlier application and need not be duplicated in detail here. The outer cylindrical face of the drum has a chart-backing surface or element 193 of a smooth, firm material but which is adapted easily to be entered by the sharp point of the marking instrument in case it pierces the paper or other material of the chart. As shown in Fig. 25 said element 193 is in the form of a cork sleeve drawn onto the drum and having a tight fit on it. The chart 192 of paper or other flexible sheet material is readily installed on and removed from the drum. In the illustrated example its lower edge is set inside one or more arcuate positioning clips 194 at the base of the drum, the overlapped end portions of the chart being brought behind one of such clips 194. At its upper edge the chart is held by a releasable clamping means such as the spring fingers 195 on brackets 196 projecting from the top of the drum 180.

Improved marking means is herein disclosed for making the record on the chart. As seen in Figs. 1, 2 and 25 the marking device or needle is removably carried at the upper end of a vertically movable marking arm 200, the vertical movements of which are controlled by the feeler and timing control mechanism to be described. The marking device comprises a cup or reservoir 201 for a supply of ink and having depending forked portion 202 adapted to straddle a button 203 near the upper end of the marker arm 200. The upper extremity of the latter is vertically slotted as at 200^a to receive a grooved portion of a nipple 204 projecting from the base of the reservoir and having an ink passage 205 communicating with the main ink chamber of the reservoir. A needle holder 206 having a needle 207 extending axially through it is received on the nipple 204, as by a Luer slip connection with it. The needle itself has a longitudinal bore or passage 207^a communicating at its rear end with the channel 205 leading from the ink reservoir 201. The passage in the needle is of small or substantially capillary diameter, such as to supply and maintain a small quantity of the ink at the outer end of the needle, in readiness for marking, but avoiding any drip. The outer end of the needle preferably is sharp pointed as illustrated in Fig. 25, for indenting or piercing the chart, this action being facilitated by the readily penetrable character of the underlying cork or like element 193.

It will be understood that as in the previous application the marker arm 200 and the described marking device on it normally stand at a level at the upper portion of the drum, at or near the top of the recording space on the chart, and that said parts are periodically allowed to drop, to an extent determined by the wear-meas-

uring feeler to be described, so as to produce a mark at a corresponding level on the chart. When so moved down into marking position, the marker device is positively moved inwardly, radially of the drum, to contact and mark the chart, and is subsequently positively retracted.

For this purpose, as seen in said Figs. 1, 2 and 25, the marker-carrying arm 200 has at its upper portion a laterally projecting vertically slotted 10 guide finger 208 which is slidable up and down, with the movement of the marker arm 200, along the adjacent edge of a vertical fin 210. The latter projects radially at the upper end of the marker-turning rod 211 which is held against vertical movement and is supported for rocking on its axis, as by means of upper and lower guide bearings 212, 213 on adjacent portions of the upper framing. A torsion spring 214 surrounding the rod 211 has one end adjustably secured 20 to it as by a collar 215 and its other end anchored in a stationary part, such as the upper bearing 212. This spring 214 acts normally to urge the vertical rod 211 in a direction to move and hold the fin 210 and the marking needle 207 away from the chart, the tension under which the parts are so held being adjustable by means of the collar 215 referred to.

The vertical movements of the marker arm 200, and the positive inward swinging and outward retraction of the marker device by the rod 211 are effected by a linkage system of a character similar in general to that of the previous application but herein embodying various features of improvement. Referring to Figs. 1 and 30 2, and also to Figs. 26 to 28, the marker arm 200 is supported by upper and lower indicator or feeler arms 220 and 221 having their outer ends pivotally connected to said marker arm 200 as at 222 and 223 respectively. Intermediate its ends the upper arm 220 has a fixed point of pivotal support, as at 224, on a strap 224^a depending from the arch member 52; see Fig. 1. The lower arm 221 likewise has a fixed pivot, as at 225, on the arch or top frame. The marker needle 207 at the upper end of the marker arm 200 is thus supported for vertical movement in a straight line and in true parallelism with the vertical feeling movement of the wear indicator, detector or feeler 240 hung on the upper arm 220 in a manner to be described.

The lower arm 221 and consequently the marker device and associated parts including the wear feeler are normally held up substantially in the position as illustrated in Fig. 1 by a removable stop 226 on said lower arm 221 projecting across the upper edge of a further supporting arm 227. The latter is pivoted at one end on the same fixed pivot 225 with said lower arm 221 and has its other end pivoted as at 228 at the upper end of a link 229. Vertical movement of this link 229 serves to let down and to elevate the marker, through the medium of a lower link 230, Figs. 3, 30 and 31, having a fixed pivot at its lower end, as at 231. At an intermediate point along said lower link 230 there is pivoted as at 232 a lift rod 233 connected by a pivot at its lower end to a cam lever 234. The latter has a fixed pivot at one end, as at 234^a, Fig. 30, and at an intermediate point carries a cam roll 235 adapted to ride on a cam disc 236. The free end of said cam lever may be weighted, as at 234^b.

The cam disc 236 is fixed on the shaft 188 previously referred to in connection with the drive for the recorder drum. It has a relatively

short and steep-walled notch 237, Fig. 30 which, on coming opposite the cam roll 235 will allow the latter and the described linkage connections to drop sharply and cause them to be lifted again after a brief interval. This conditioning of the linkage system for down movement occurs once for each rotation of the disc 236, which has an accurately predetermined and generally relatively short period of revolution per minute. Said linkage motion actually takes place, however, only when permitted by other control mechanism to be described in connection with Figs. 29 to 32.

Considering again the marker turning rod 211 as best seen in Figs. 1 and 2, improved means is provided for positively rocking said rod to move the marker needle 207 into contact with the chart and to retract it. These movements are respectively opposed and aided by the torsion spring 214 already described. The actuating force for the movements is derived from the lowering and lifting action of the marker arm 200 and its associated link connections, and herein directly from the lower supporting arm 227 and its connected link 229. Said arm 227 has a laterally projecting pin 227^a which in the course of the down movement of the arm is adapted to enter a slotted formation 227^b at the end of one arm of a bell-crank 227^c on a fixed pivot 227^d on the lower arm 53 of the top frame. The other arm of said bell-crank is pivotally connected by an adjustable link 227^e to lateral finger 211^a on the lower portion of the rod 211. Thus during the descent of the arm 227 its pin 227^a engages and rocks the bell-crank in a counter-clockwise direction as viewed in Fig. 1. This in turn rocks the rod 211 in a positive, firm manner, in the direction to swing the vertical fin 210 in toward the chart and to cause the needle 207 to make a mark on it. By reason of the interengagement of the pin 227^a in the slot 227^b of the bell-crank a reverse turning of the latter is affected during the subsequent raising of the link 229 and arm 227. The rod 211 accordingly is reversely rocked to swing the fin 210 away from the chart, positively retracting the needle, supplementary to the influence of the spring 214.

The described linkage and cam mechanism associated with the marker arm 200, together with said further controls of Figs. 29 to 32 determines the times at which the periodic measurements and recordings shall be made, by allowing the marker mechanism and the wear detector or feeler 240 to move down at the selected intervals. The extent of this down movement is in direct ratio to the depth of wear which has been effected on the specimen at the given time, as detected or measured by the feeler element 240 which engages or feels directly on the worn surface of the specimen. Said feeler as herein disclosed is of improved construction, whereby possible irregularity in its positioning is substantially reduced, the feeler being enabled in effect to float on the specimen and to give an indication of the average height or depth of the worn area of the specimen contacted by it. Novel provisions are also herein made whereby the ratio of the markings on the chart to that of the actual distance of wear may be varied, so that the vertical extent of the curve plotted on the chart may be made greater or less, to suit different conditions. For example, with a relatively thick specimen to be tested, such as a heavy Axminster carpet the total wearing-depth and accordingly the increments to be measured are relatively large, so that a charting ratio of perhaps ten to

one or even less may be adequate to plot a curve on which the successive points are adequately spaced vertically for convenient reading. With other materials, with which either the incremental or the total wear is smaller, larger charting ratios may be desirable, such, for example, as twenty to one, fifty to one or even greater.

Referring in this connection to Figs. 1, 2 and 26 to 28 inclusive, the feeler or detecting device proper comprises a flat disc, plate or caliper button 240, preferably having an inwardly and downwardly bevelled edge portion, to facilitate its seating on the specimen. In the illustrated example this feeler button has an area of approximately 1 1/2 square inches. At its upper face is a central stem 241 terminating in a ball 242. The ball 242 is movably received in the lower end of a socket member 243 which is spun over at its bottom edge as illustrated, sufficiently to retain the ball 242 while affording to the feeler button 240 a universal or floating movement relative to the socket member, and enabling it to tilt in any diametral plane.

The socket member 243 is adjustably threaded at the lower end of the feeler rod 244 the upper end of which in turn is adjustably threaded into a top-piece or cap 245 through which the feeler is connected to the upper arm 220 of the parallel linkage system, in any one of a number of different positions relative to it. It will be seen that the universal connection between the feeler head or button 240 and its supporting rod, and which permits the feeler head to float or tilt relatively to the rod, affords a greater degree of accuracy in measuring the average depth of the portion of a test specimen onto which the feeler is let down. For example, if some small area of the specimen, less than that of the feeler head, stands at a higher level, such as a small hump or projection of any kind, the portion of the feeler head diametrically opposite such elevation will tilt down to the lower level and allow the feeler rod to come down to a level intermediate the lower one and that of the elevation. Thus in effect the feeler indicates the average level of the contacted worn surface. The feeler rod 244 as shown has a knurled head 244^a fast on it to facilitate turning the rod for length-adjusting purposes, and whereby the feeler may quickly be set for cooperation with any given specimen. A knurled lock nut 244^b desirably is threaded on the rod adjacent the cap piece 245 for locking said parts in the desired relative position of adjustment.

The feeler-rod supporting cap 245 has a lower forked portion 246 through which the upper linkage arm 220 extends, and an upper forked portion 247. Intermediate these two forked portions is a laterally projecting arm 248. Each of the three portions of the feeler-rod cap 245 referred to has an aperture for the reception of a removable pin 249 for use in connecting said cap 245 to the upper arm 220 in three different positions of adjustment, as shown for example in Figs. 26, 27 and 28 and which positions will hereinafter be referred to as positions A, B and C as indicated on said figures.

In position A, that of Fig. 26, the removable pin 249 is set in an aperture 250 in the lower slotted portion 246 of the cap 245 and through a corresponding aperture 251 in the arm 220 (these apertures may be seen unobscured by the removable button, in Figs. 27 and 28). In this A position, of Fig. 26, the cap member 245 of the feeler rod is directly connected to the arm 220

and in such manner that the ratio between the feeler movement, in traversing the total worn depth to be measured, and the corresponding movement of the marker device 207 is relatively small, that is, nearest to a direct or 1 to 1 ratio. In the example illustrated this A position of the parts affords a 10 to 1 ratio between the distance measured off and marked on the chart and the actual corresponding worn depth indicated.

In each of Figs. 26 to 28 inclusive the feeler 240 is shown in the same lowermost position, in which it is assumed to be down in contact or substantially in contact with the bare platen. This bottom level is indicated by the dot-and-dash line *b—b*, at the bottom of each of said figures. The initial level of the test specimen, that is, the level at which the feeler makes its uppermost marking indication is shown in the several figures by the dot-and-dash line *a—a*, spaced above the bottom level lines *b—b*. The corresponding positions of the arm 220 are indicated at the upper portions of said figures by the dot-and-longer-dash lines *a—a*, *b—b*.

From a comparison of said Figs. 26, 27 and 28 it will be noted that the initial or *a—a* position of the arm 220 and the final or *b—b* position of said arm is the same in each of the adjusted positions of the parts, but the feeler 240 starts its indications at succeeding lower levels. That is, while the total angular movement of the arm 220 is always the same, the vertical movement of the feeler 240 differs. In Fig. 26 the relatively large vertical movement of the feeler between the wear lines *a—a* and *b—b* at the bottom of the figure corresponds to a marking movement of the arm 220 through the angle between the lines *a—a* and *b—b* at the upper portion of the figure. In Fig. 27 the lesser feeler movement, between the wear lines *a—a* and *b—b* of that figure again corresponds to the same total marking movement of the arm 220 between the lines *a—a* and *b—b* adjacent it, while in Fig. 28 a still smaller feeler movement corresponds to this same total movement of the arm 220.

Or to put it conversely, and going from Fig. 28 to Fig. 27 to Fig. 26 the same incremental movement of the feeler 240 effects a proportionately decreasing corresponding angular movement of the arm 220. Thus with the C-setting as in Fig. 28 a relatively minute movement of the feeler, say of the order of .002 inch is enabled to effect markings on the chart spaced say .1 inch (i. e. 1 to 50) and hence at adequately spaced points for clear reading purposes. The resulting markings may if desired be substantially as widely spaced vertically with said C-setting as with the small ratio or more nearly direct A-setting, (1 to 10 for example) the B-setting affording an intermediate ratio, such as 1 to 20. The horizontal graph lines on a given chart, indicative of wear levels, when used in the three different A, B and C-settings of the feelers, might represent actual increments of wear of the specimen such, for example, as .010 inch, .005 inch and .002 inch for said three cases.

It will be understood that by "feeler movement" as here referred to in connection with the lower lines *a—a* and *b—b* is meant the increasing distance to which the feeler descends at succeeding time intervals as the wear deepens during any given test specimen, it being further noted that, as in the preceding application, the feeler normally is elevated, substantially as in Figs. 1 and 2, above and out of contact with the specimen and in making each periodic measurement it may

have a preliminary down movement before contacting the surface of the specimen. The extent of this preliminary movement varies with specimens of different thickness and with the corresponding different adjusted positions A, B and C of Figs. 26 to 28. This is compensated for by adjusting the length of the rod 244 below the top-piece or cap 245 as permitted by the threaded adjustable connection between said parts. In comparing these three figures it will be noted that the feeler-rod length below the cap 245 is greater in Fig. 27 than in Fig. 26 and still greater in Fig. 28.

The mechanism by which the different adjusted positions B and C of Figs. 27 and 28 respectively are obtained comprises two links 252 and 253 having their adjacent ends pivotally connected as at 254. The vertical and longer link 252 is pivoted at its lower end to the arm 220 at 255 while the shorter and more nearly horizontal link 253 is pivotally hung on the upper frame member 52 as at 256.

The lateral finger 248 of the cap 245 has a pin-receiving aperture 257 adapted to cooperate with a similar aperture 258 in the vertical link 252. Similarly the upper slotted portion 247 of said cap piece has a pin-receiving aperture 259 for cooperation with an aperture 260 in the upper link 253.

For the setting B, of Fig. 27, the pin 249 is removed from its position as shown in Fig. 26 and is inserted in the apertures 257, 258 of the lateral finger 248 and the link 252, the parts being manipulated to bring said apertures into alignment. In this B position the connection between the feeler rod 244 accordingly is through the lower portion of the cap member 245, through the lateral finger 248 thereon and thence through the lower portion of the link 252 onto the arm 220 at the pivot point 255.

For the C position, of Fig. 28, the parts are manipulated to bring the aperture 259 at the upper end of the cap 245 into alignment with the aperture 260 of the horizontal link 253 and the pin 249 is then inserted in said aligned apertures. As seen in Fig. 28 the connection from the feeler rod 244 is then up through substantially the full length of the cap 245, through the outer end portion of the link 253 and downwardly through the full length of the vertical link 252 onto the arm 220 at the pivot point 255.

Releasable means desirably is provided for holding the pin 249 in its several different adjusted positions. In the illustrated example this is effected by an annular slot 249a in the neck of the pin 249 and adapted to have locking engagement with wire-like spring fingers 249b and 249c fixed on the cap member 245. Said spring element 249b is vertically extended to have locking cooperation with the pin 249 when the latter is either in the lower aperture 250 or in the upper aperture 258, as seen in Figs. 26 and 28, while the intermediately located finger 249c is positioned to snap into said locking slot 249a of the pin when the latter is in the intermediate aperture 257 of the laterally projecting finger 248, as seen in Fig. 27.

It is desirable that the feeler button 240 shall engage the test specimen with a predetermined and adjustable pressure, and also that the same predetermined pressure be maintained when using the different calibrations or marking ratios corresponding to the positions A, B and C referred to. Accordingly, as seen in Fig. 1, the upper arm 220 is accurately balanced or loaded

to the extent necessary for said purpose, as by means of a balance adjuster slide 220^a movably received on said arm and retained at various points along it as by the spring ball detent shown or other like device cooperable with notches or the like formations on the arm. A stop may be provided to retain the slide against running off at the free end of the arm 220. The latter may additionally be apertured at its free end for hooking on various weights if greater pressure by the feeler is desired. The adjuster slide may have a pointer element such as illustrated, for cooperation with a scale along the arm 220 graduated in units of feeler pressure or loading. The appropriate setting for the balance slide 220^a to give a same predetermined feeler pressure for the three ratio settings A, B and C may be distinctively marked on the arm 220 as indicated by the letters A, B and C on Fig. 1.

As best seen in Fig. 2 and also in Figs. 5 and 11 the feeler rod 244 is additionally guided in its up and down movements as by a guide arm 260 depending from the lower arm 53 of the top arch or frame. As previously mentioned the dirt-retaining glass plate 110 is apertured at 116, Fig. 11, for passage of the feeler rod.

From the foregoing it will be understood that the described feeler and the associated marking device, the marking level of which is controlled by the feeler, are permitted to descend periodically to take a wear measurement and making a recording thereof. As previously mentioned, means is herein provided whereby the times at which such measurement and recording are had may be selected so as to occur relatively frequently, or only at longer intervals. With some types of material to be tested it is also desirable that wear measurements and recordings should be made at comparatively frequent intervals during the initial portion of the test but thereafter only at longer intervals. For example, with Axminster rugs and other tufted or pile fabrics, in the earlier stages of the test the indicated wear or thinning of the specimen is comparatively rapid, the pile being matted or worn down to a certain initial extent comparatively quickly but thereafter wearing down much less rapidly. That is, the wear curve plotted on the chart descends very steeply at first and then levels off. Hence if the readings for the opening stage of the test should be taken only at the longer intervals appropriate for the latter stages, the first markings on the chart would be comparatively widely spaced vertically. To fill in such a gap with one or more intermediate markings an initial short-interval measurement and recording is herein made possible.

Referring now to Fig. 3 and to the detail Figs. 29 to 32 inclusive, the vertical link 233 and the arm 234 carrying the roll 235 which cooperates with the cam disc 236 are normally held up in raised position as seen in Figs. 3 and 30, wherein the feeler and the marker are likewise elevated, by means of a finger 265 having a dog 266 at its upper end engaging beneath a boss 267 on said link 233. The main upper portion of the arm 265 as illustrated is of spring material, so that in certain positions of the parts the arm may spring back away from the link 233 and permit the latter to rise past the dog 266 and into the 70 illustrated position of Figs. 3 and 30.

Said spring portion 265 is fastened to a short arm 268 on a sleeve 269 rotatably supported on a stud 270 projecting from an adjacent fixed part of the lower framing. Said sleeve 269 also has 75

secured to it, in the manner of a bell-crank, a lower arm 271 carrying a roll 272 cooperating with a set of interval-controlling elements or discs by adjustment of which the initial short-interval and subsequent long-interval measurements or readings may be had.

This adjustable control unit, indicated as a whole by the numeral 290 and to be referred to in more detail later, is mounted on one end of the horizontal shaft 275 previously referred to as having the worm 185 fast on it. Said shaft continues loosely through the bearing bushing 186^a for the worm gear 186 and axially beyond the latter, to receive end bearing support in a bracket 276, Figs. 29 and 30. Also loose on said shaft 275 is a large gear 277 fast with the hub of said worm gear 186. Spaced from said gear 277 and also loose on the shaft 275, adjacent its end in the bearing 276, is a smaller gear 278. These gears are suitably held in spaced relation on the shaft 275 and their hubs, at their adjacent faces, are provided with clutch formations for engagement with a clutch sleeve 279 keyed on the shaft 275 for rotation with it but slidable thereon for alternative engagement with the small gear 278 or the large gear 277 thereby selectively to couple either of the latter to the shaft 275.

As seen in Fig. 29 a short stud shaft 280 is provided adjacent and paralleling the shaft 275 and having its inner end fast in a boss supported from the bracket 189 before mentioned. The bearing bracket 276 shortly above referred to is secured as by a set screw to the outer end of this parallel stud shaft 280. Rotatable on said stud shaft is a sleeve 281 having secured at one end a small gear 282 meshing with the large gear 277 on the hub of the worm gear 186, said sleeve having at its other end a larger gear 283 having meshing engagement with the smaller gear 278 loose on the shaft 275. The described gearing constitutes a change-speed mechanism whereby the shaft 275 and hence also the record drum 180 on the recorder shaft 182 may be connected in driven relation with the worm gear 186 at either of two speeds.

By shifting the clutch collar 279 toward the right in Fig. 30 the worm gear 186 is directly coupled through its hub and that of the adjacent large gear 277 to the shaft 275. By shifting the clutch sleeve 279 toward the left in Fig. 30 the smaller gear 278 is coupled to the shaft 275. The drive is then from the worm gear 186 and the coaxial large gear 277 to the smaller gear 282 on the sleeve 281 and through the larger gear 283 also on said sleeve, to said smaller gear 278 and hence to the shaft 275 then coupled to the hub of said gear 278. It will be noted that with the parts connected as last described, that is, with the small gear 278 coupled to the shaft 275 by the shifting of the clutch sleeve to the left in Figs. 29 and 30, the shaft 275 is driven at a higher speed, through the described step-up gearing arrangement, as contrasted with the slower or 1 to 1 drive ratio between the worm gear 186 and the shaft 275 when said worm gear is in effect coupled directly to said shaft, by throwing the clutch sleeve 279 to the right in said Figs. 29 and 30.

As will be apparent from the further description the described driving of the shaft 275 at the higher speed is adapted to effect measurements and recordings at regular but relatively short or frequent intervals, say for example every five minutes, while at its slower rate of drive the

regular measurements and recordings are had at greater intervals such for example as every twenty minutes. The long intervals and the short intervals may be otherwise proportioned, as determined by the ratio of the gearing 277, 282, 283 and 278 in the change-gearing described. It should also be noted that such shifting of the speed of shaft 275 produces the same proportionate change in the drive of the recorder drum 180, since the latter is driven from the worm 185 fast on said shaft 275 and meshing with the worm wheel 184 on the recorder shaft 182. Such corresponding change in the drum speed and hence of the angular travel of the chart 192 thereon is desirable so as to produce a wider horizontal or peripheral spacing between successive short-interval markings, preferably to the same extent as for the longer-interval markings.

Means conveniently available to the operator or person conducting the tests is provided for shifting the clutch sleeve or coupler 279 into and to retain it in either of the described positions. For this purpose, as illustrated in Figs. 29 and 30, said clutch sleeve has a circumferential slot receiving an eccentric 284 on a collar 285 pinned at the lower end of a time-shift rod 286 guided in the lower framing and extending upwardly through the platform 2. This shift rod has a manipulating button or knob 287 at its upper end, and also a pointer 288 for visually informing the operator as to the position of the clutch sleeve 279, that is, as to whether the apparatus is set for fast, short-interval readings or to read at the slower, longer intervals. Since the clutch and associated parts, in fact all the operating mechanism, is housed in the cabinet 1, the operator might otherwise have difficulty in quickly determining the operating status of the machine. Said pointer is movable between appropriately located stops or indices 289, 289^a corresponding to the two clutch settings respectively. Appropriate indicia may be provided adjacent said stops such as F and S for fast and slow, or "5-minute" and "20-minute" respectively, or such other intervals as may be used in the given instance.

It will be understood that the clutch sleeve 279 is at all times, during operation of the machine, in one or the other of its engaged positions, its intermediate or central position as shown in Figs. 29 and 30 being only momentary, it being assumed for the purposes of said figures that the clutch sleeve is in the process of being thrown in one direction or the other, by manipulation of the knob 287. Means desirably is provided, for throwing the clutch sleeve into and holding it in its two positions. As represented for example in Fig. 30 the shift rod 286 has fast on it a bevelled end dog 286^a engaged by a spring-actuated camming arm 286^b mounted so as to be toward the end of the dog. As the latter moves past center said arm snaps onto one or the other of the inclined ends of the dog, camming it angularly about the axis of the rod 286 and thereby moving and holding the latter and the clutch sleeve in the selected position of adjustment.

Rotation of the shaft 275, in the direction of the arrow thereon near its right end in Figs. 29 and 30 not only actuates the recorder drum but also operates through the control disc or plate unit 290 previously mentioned to exercise a master control as to the time a measurement is to be made. Appropriate positioning of said unit

290 allows the associated roll 272 and arm 271 carrying it to drop, thereby to turn the sleeve 269 so as to withdraw the spring arm 265 from its normal position below the boss 267 in which it prevents descent of the link 233 even though such descent might be permitted by the cam disc 236 and its cooperating cam roll 235.

This time-controlling unit 290 includes a pluri-notched short-time plate 291 fast on the shaft 275, its hub 291^x being secured thereto as by a set screw or the like. This plate 291, hereinafter referred to as the initial-period or "5-minute" plate acts in a controlling capacity only for effecting a comparatively small number of relatively closely timed and unusually initial readings. At other times it acts simply as a driver for the other main parts of this unit 290. Loose on the shaft 275, adjacent the initial-period plate 291 is a semi-circular coupling plate or coupler 292. Beyond the latter and also loose on the shaft is a further plate 293, hereinafter referred to as the normal-control or normal-period plate. This latter has but a single notch 293^a for entrance of the roll 272.

When the machine is being operated to give readings or recorded measurements at regular intervals, whether these intervals be short or long, the time at which a measurement shall occur is determined by the dropping of the roll 272 into the notch 293^a of this normal-period plate 293. Although the roll is of a length to extend across both plates 291 and 293 one of the notches of the first plate 291 normally is always in line with said single notch 293^a of the normal-control plate 293. Under such conditions the measuring interval is further determined merely by the speed of the shaft 275 as controlled by the positioning of the clutch member 279, the shift or control knob 287 being set for fast or slow marking as desired. The marking intervals under such "normal" operation, whether short or long, are in either case equal or regular.

The normal-period plate 293, while loose on the shaft 275, is secured to the hub of a bevel pinion 294, Figs. 3, 29 and 30 which also is loose on said shaft. This pinion 294 meshes with a similar bevelled pinion 295 fast at the lower end of a vertical indicator rod 296 journalled in the lower framing and extended upward through the platform 2, similarly as the clutch rod 286. At its upper end is a manipulating knob 297 and an indicating pointer 298. Adjacent the outer end of the pointer is an index 299 so positioned with relation to the described parts that the arrival of the pointer 298 opposite it will afford a visual indication that a measuring and recording operation is in process or about to take place. By noting the position of the indicator 298 relative to the index 299 at any time, the progress of the measuring interval may be observed, whether the mechanism be set for short time or long time measurement. For example, under a 20 minute setting, if the pointer is diametrically opposite the index 299, this shows that the marking interval is half over. The same is true for a five minute or other setting.

The two plate elements 291 and 293 of the control unit 290 are adapted to be variously connected in driving or non-driving relation through the intermediate plate or coupler 292 and through a pin 291^b at the inner face of the initial-period plate 291 and a pin 293^b on the adjacent inner face of the normal-interval plate 293. These two

pins are located at different radial distances from the axis of the shaft 275 so that at certain times they may pass each other. They are also positioned for overlapping engagement with one or the other radial edges or end faces 292^a and 292^b of the coupler 292, in the various different positions of the parts now to be explained.

When the mechanism is set for "normal" operation, that is, to take readings at equal time intervals from the start of the test and continued throughout, and irrespective of whether the setting, as controlled by the shift-clutch 279, is for the shorter intervals or the longer ones, the position of the three elements 291, 292 and 293 of the control unit 290, at the time for each reading, is that illustrated in the partly diagrammatic or exploded view, Fig. 32. At such time the notch 291^a of the disc 291, the notch nearest the pin 291^b on said disc, is at the top, in position to allow the roll 272 and its carrying arm to drop. So also is the notch 293^a of the other disc 293. These two notches thus being aligned, the roll 272 drops, releases the link 233. Since the notch 237 of the cam or master disc 236 is arranged also then to be at the top, opposite the cam roll 235, the feeler and marker mechanism descends and effects a measurement and marking.

In the described position of the three parts of the unit 290 they all revolve as one, the first disc 291 driving the connector disc 292, in the clockwise direction as indicated by the arrows in Fig. 32 and the latter in turn driving the second disc 293. A spring 296^a surrounding the indicator and setting shaft 296 and bearing downwardly on the pinion 295 puts sufficient load on the latter to hold the disc 293 and connector plate 292 against overrunning and keeping the pin 293^b in engagement with the connector plate at its radial face 292^b, and the radial face 292^a of said plate in abutting relation with the pin 291^b of the first disc.

Assume now that it is desired to have the readings occur at certain regular intervals throughout the major portion of the test, say 20-minute intervals, but to have them made more frequently during the first 20-minute interval, or for that matter during some subsequent regular interval. In other words, it is desired to sub-divide the initial or other regular interval into an equal number of shorter intervals. With a short-interval or sub-dividing disc 291 having four notches as illustrated in Fig. 32 the division is into four equal shorter intervals; for subdividing into some other number of shorter intervals a corresponding number of notches would be provided.

This subdividing of the regular marking interval, either at the start of a test or at some subsequent time, is effected by turning the setting knob 297 at the upper end of the indicator and setting shaft 296 ahead, in the same direction on which it is rotated by the shaft 275, as indicated by the arrow adjacent said knob 297 in Fig. 30, and by the other rotational arrows in said figure and in Figs. 29 and 32. The shaft 296 is so turned until it has advanced the single-notch disc 293 through 360° relative to the shaft 275 on which said disc and the connector plate 292 are loosely mounted. It will be observed that the pin 293^b on said disc 293 is at the bottom of the latter in the normal position thereof as shown in Fig. 32, said pin being diametrically opposite the notch 293^a.

The first 180° or half-turn advance of the disc 293 shifts pin 293^b to a top position, bringing it up against the then upper radial face 292^a of the connector plate 292. Continued advancing of the disc 293 in the manner referred to then causes said pin 293^b to pick up the connector plate 292 and advance it with the disc 293 through the second 180° or half turn of the latter. This accordingly brings the connector plate 292 round to a diametrically opposite position from that of Fig. 32, so that its radial face 292^b is brought to the top but behind the pin 291^b of the plural-notch disc 291, and the other radial face 292^a is carried down to the bottom, away from and 180° in advance of said pin 291^b.

With the parts of the unit 290 so disposed and the apparatus being started up or continued in operation, the first wear measurement and marking will take place when the disc 291 has made a quarter-turn, bringing its next notch 291^a to the top. The releasing roll 272, which is of a length to extend across both discs 291 and 293, as seen in Figs. 29 and 30, can then drop because the disc 293 has not been turned during this quarter-turn of the shaft 275 and disc 291. This is so because the radial faces 292^a and 292^b of the connector plate initially stood 180° ahead of the pins 291^b and 293^b respectively. During this first quarter-turn the pin 291^b moves down clockwise, Fig. 32, through 90° of arc, but is still 90° away from the radial face 292^a of the connector plate.

After this first short-interval marking, resulting from the notch 291^a coming to the top, the plural-notch disc 291 continues another quarter-turn, bringing the next notch 291^a to the top. As the connector plate 292 has not yet been turned, the disc 293 has continued in its position of Fig. 32, so that its slot 293^a remains at the top and aligns with said second notch 291^a of the disc 291. Another measurement and recording accordingly takes place. At this time the pin 291^b has advanced 180°, to a bottom position, in which it brings up against the radial face 292^a of the connector plate 292.

Another quarter-turn of the shaft 275 and disc 291 accordingly causes the latter to pick up the connector plate and move it 90° to a position in which its radial faces are horizontal, face 292^a being at the left, looking at Fig. 32, and directly above the pin 291^b (which has now advanced 270° from its initial or Fig. 32 position) and face 292^b being horizontal but still 90° behind the pin 293^b of the single-notch disc 293. The latter accordingly still has not been turned, its notch remains at the top in position to align with the notch 291^a of disc 291, and the third short-interval marking takes place.

During the next-following or fourth quarter turn of the shaft 275 and plural-notch disc 291 the three main parts 291, 292 and 293 of this unit 290 arrive again in the relative positions as shown in Fig. 32, the connector plate 292 being carried around another quarter turn, to its illustrated position, bringing its radial face 292^b into abutting position behind the pin 293^b of the single-notch disc 293. The pin 291^b of the plural-notch disc 291 has likewise returned to abutting position behind the radial face 291^a of the connector plate. The single-notch disc 293 still has not been turned and accordingly, as the notch 291^a of the plural-notch disc 291 comes to the top a fourth short-interval measurement and marking takes place.

Since the parts have now arrived at the position in which they turn as a unit, being driven from the shaft 275 through the disc 281, the connector 282 and onto the single-notch disc 283, a measurement will thereafter have been had only for each revolution of said single-notch disc 283, as its notch 293 comes to the top, at such longer but regular intervals as represented by a single revolution of said part 283.

For example, if the gearing ratio is such that under a "slow" or "long-interval" setting of the shift knob 287 and clutch 279 the shaft 275 and disc unit 290 is revolved once each twenty minutes, then a reading will be made regularly at 20-minute intervals, and the four sub-divided or short-interval reading as above described occurred at 5-minute intervals, the first at the end of five minutes, the second at ten minutes, the third at fifteen minutes and the fourth at twenty minutes, with regular readings thereafter only at the longer 20-minute intervals. It will be understood that if the shift-knob 287 and the clutch 279 controlled by it are moved to their "fast" or shorter-interval setting wherein the shaft 275 is driven at a greater speed, so that the regular marking intervals are cut down to say five minutes, than such quicker or 5-minute intervals may similarly be sub-divided, into four still shorter intervals in the illustrated instance, by adjustment of the control-unit 290 through advancing the setting knob 297 as described. Such sub-divided readings would then occur at one-and-one half minute intervals, during the initial or other regular interval, whenever said adjustment is made.

To summarize, the measurement time control mechanism as disclosed is such as to effect regular short-interval readings (that is, wear measurements and recordings) at say 5-minute interval, or alternatively regular long-interval readings, at say 20-minute intervals. This selection is made by the shift-knob or selector 287 by means of which the clutch member 279 is thrown to couple the sheet 275 for "low-speed" or "high-speed" operation. The ratio between said short and long intervals depends on the ratio of the described change-speed gearing, which may be other than the 1 to 4 ratio mentioned by way of example. In addition, the control mechanism may be adjusted, by manipulation of the setting knob 297, to sub-divide any regular reading interval into a number of shorter ones, such sub-division being into four shorter intervals in the illustrated mechanism shown by way of example. Other fractional interval or sub-divided reading periods may be had by providing a different number of notches, whether two, three, six or other number, in the plural-notch disc 281. Accordingly, for example, the machine may be set to give readings at five, ten, fifteen and twenty minutes from the start of a test and thereafter at the end of each twenty minutes. Or, using the "fast" or short-interval regular readings, it may be set to read initially at one and one-quarter minutes, two and one-half minutes, three and three-quarter minutes, and five minutes from the start of a test and thereafter at the end of each five minutes. Any subsequent regular marking interval, whether short or long, may be similarly subdivided. It will be understood that the specific time intervals mentioned, such as 5-minutes, or 20-minutes, while found to be convenient periods for wear curve plotting by markings on the chart, are

given as examples only, and that other intervals, either shorter or longer, may be employed, depending on the ratios of the described drive and gearing mechanism.

5 It will also be noted that, as in the earlier application, there is a very large reduction in the drive of the recorder drum shaft 182, first through the small and large gears 12 and 11 of Fig. 3 and subsequently through three successive worm and worm gear pairs, namely the pair 10, 9, the pair 187, 188 and finally the pair 185, 184. The recorder drum accordingly turns slowly, for example, once each 24, 36 or 48 hours, or some similar period, so that the one chart may cover 10 such total period. For longer tests, which may extend up to 72 hours or more, larger diametered drums may be used, accommodating a longer chart, or the drive ratio for the drum may be 15 altered to condense the plotted curve circumferentially of the drum.

20 On Fig. 1 several elements not previously referred to are shown. These include the lifter hook 300 hung on a short arm 301 on a collar, at the opposite face of the arch from that seen in Fig. 1, on a pivot 302 and connected to a hand lever 303. The hook is adapted to engage under an extension of the pivot 123 of the shoe lifter arm and, by rearward swinging of the hand lever to elevate the shoe and hold it up off the 25 platen. In such raised position the short arm 301 throws up a cross center so as to hold the hook up, said arm being stopped in said holding position by engagement of the lever 303 with a stop 304 on the upright 55.

30 35 As seen at the lower left portion of Fig. 1 the arch-forming casting or frame member 51 containing the conduit for the debris desirably is provided with a supplemental or lower clean-out and inspection door or aperture, normally closed by a cap 85^a having an operating knob 86^a, said parts being similar to the corresponding parts at the upper clean-out and specimen-securing aperture at the top center of the arch.

40 45 In a similar manner as in the earlier application the up and down, impacting action of the wearer shoe may be dispensed with if so desired. In order so to discontinue the impacting action the removable pivot pin—connecting the lift rod 124 and its operating lever—is withdrawn, rendering the lifter mechanism inactive. Thus, as may be desired for various different materials to be tested, the wearing action on the specimen may be continuous and without impact, or may be intermittent, for example, 50 thirty-eight engagements per minute, and with impact. Moreover, by means of the micrometer adjustment device 132—136 the shoe may be set to operate at any desired level relative to the specimen, and such operation may be with impact or without impact, and either continuous or intermittent, in either instance. Moreover, by means of the adjustable weight 130 the pressure of the shoe on the specimen may be regulated as desired. For example, in one embodiment the weight of the shoe, having 5 1/2 square inches of wearing surface area and its shaft and immediately associated parts, is about 12 lbs. With the other operating parts such shoe, with no additional weight at 130 places a total weight on the platen of 30.12 lbs. or 5.48 lbs. per square inch. By reason of the leverage involved the addition of a 10 lb. weight at 130 places a total weight on the platen of 55.22 lbs. or 10 lbs. to the square inch. A 20 lb. weight brings the total 55 60 65 70 75

weight on the platen to 80.32 lbs. or 14.7 lbs. per square inch, while a 30 lb. weight places a total weight of 105.42 lbs. on the platen, or 19.2 lbs. to the square inch. Other desired pressures may be had by adding to or subtracting from the weight 130.

The enlarged laterally projecting apron 4 for the platen preferably is constructed to have a weight of 150 lbs. or thereabouts. With such heavy or massive construction objectionable vibration of the apparatus in the course of a testing operation is substantially eliminated. Further in this connection the operating speed of the machine may be varied and adjusted as by means of the variable speed pulley such as illustrated for receiving the drive from the motor.

It will also be understood that various other constructions for the wearing surface may be employed, in addition to those previously referred to. For example, the shoe may have an entirely plain, uninterrupted under face, free of channels such as those of Figs. 17 to 21. In such case air-cooling passages such as 68^a, 69^a of Figs. 20 and 21 or 65^a of Fig. 11 generally are provided.

A thermally-responsive stop motion associated with the wearer shoe has been described herein. Other stop motions may be provided and are herein illustrated in Figs. 1 and 15, and in connection with the wiring diagram, Fig. 16. Referring to the upper right portion of Fig. 1, and to Fig. 15, one stop motion as there shown is associated with the feeler measuring mechanism and is adjustable so as automatically to stop the machine at any desired depth of wear of the specimen. Said stop devices include a contact finger 310 having a threaded upper portion whereby it is supported with capacity for vertical adjustment in an arm 311 mounted on a stud 312 projecting from the arch member 54 and insulated from it as by the non-conducting bushing 313. The contact finger has an adjusting head 314 at its upper end and a lock nut 315 for securing it in adjusted position. Said finger is adapted to engage and make electrical contact with the free end of the upper arm 220 of the feeler linkage system, thereby to establish a motor-stopping circuit. Raising of said arm being proportional to the down movement of the feeler, the contact finger may be set to stop the machine at any detecting position of the feeler. It will be understood that said arm 220 is electrically grounded on the machine, and the circuit is through a conductor 316 connected to the stud 312 and insulated from the machine and its framing, as seen in Fig. 15.

Herein on the same stud 312 there is hung a strap 320, in electrical contact with the stud but insulated from the machine. At its lower end this strap has a foot 321, Fig. 1, carrying a vertically adjustable threaded contact point or screw 322. Said contact 322 stands below the lifter arm 98 for the wearer shoe and is adapted to have motor-stopping contact with the latter at any desired level of the shoe during the wearing of a specimen. This contact accordingly may be set to stop the machine either when or just before the specimen is completely worn through or at any other selected height of the latter. The two described stop motions in effect afford a check one on the other.

The main starting and stopping switch buttons for the machine may be positioned at any convenient point. At the lower left portion of Fig. 2 a switch unit 325 is shown mounted in the edge

of the platform 2, and including "on" and "off" buttons 326 and 327 respectively.

Fig. 16 shows a schematic diagram of the electrical connections. The mains are represented at 330, 331. A transformer T is connected across them, for supplying a low voltage current, such as 16 volts, for the starting and stopping circuits. One side of the low voltage supply from the transformer is grounded as indicated, the other side being connected through a line 332 with a lead 333 connected to one pole of the "on" switch and, through two poles of the relay switch R to the relay switch-operating coil C. From a brief inspection of said diagram it will be seen that by depressing the "on" switch a circuit is established through the relay coil, acting to throw the relay switch R to the left in Fig. 16. This closes the motor circuit, through the motor leads 334, 335 and also closes a coil-energizing or maintaining circuit through the coil C, so that the relay switches remain closed although the "on" button or switch is released after being depressed but momentarily. It will further be seen that the "off" button, the thermal contact element 70^a, the feeler arm contact 310 and the shoe lifter arm contact 322 are each so disposed in a low voltage circuit that the making of the contacts thereat grounds them and in effect short circuits or cuts out the relay coil C. Hence the relay switches R open and the motor is shut off.

The transfer, relay and other associated electrical parts, aside from the motor 15, may be housed in a suitable box located in the cabinet 1.

Our invention is not limited to the particular embodiments thereof herein illustrated or described, its scope being pointed out in the following claims.

We claim:

1. In a wear-testing apparatus of the character described, in combination with a frame, a support thereon for a test specimen, a wearer shoe engageable with a specimen thereon to wear it to increasing depths, a vertically movable supporting arm for the shoe, an electric motor to drive the apparatus, a contact element supported on but insulated from the frame in position below the shoe supporting arm, for engagement thereby at a selected wear depth, a motor switch, and a relay to operate the latter, said relay disposed in a circuit including said shoe supporting arm and said contact element, thereby to stop the motor at a predetermined level of wear of the specimen.

2. In a wear-testing apparatus of the character described, in combination with a frame, a support thereon for a test specimen, a wearer shoe engageable with a specimen thereon to wear it to increasing depths, feeler means for measuring the depth of wear, an electric motor to drive the apparatus, a motor switch, a control circuit for the latter including a relay to operate the switch, and relay controlling means in said circuit including a contact carried by a stationary part and engageable by a portion of said feeler means also in said circuit so as to be actuated on wearing action of the wearer shoe to a predetermined depth, thereby to stop the apparatus upon arrival of the predetermined extent of wear of the specimen.

3. In a wear-testing apparatus of the character described, in combination, a frame, a support thereon for a test specimen, a shoe for effecting a wearing action on a supported specimen, a shaft carrying said shoe at one end, a sleeve bearing rotatably receiving an intermediate portion of said shaft, means supporting the sleeve bear-

ing for longitudinal reciprocation toward and from the specimen, collars on the shaft respectively adjacent the ends of the sleeve bearing, anti-friction bearings between the sleeve bearing and said collars, whereby the shaft is supported for longitudinal reciprocation by and with the sleeve bearing, means to rotate the shaft in the sleeve bearing, a laterally projecting annular cup on and moving with the sleeve bearing between the shoe and the adjacent anti-friction bearing to trap lubricant and dirt and a further plate-like element below and of greater lateral extent than said cup, said element being stationarily supported and apertured for the passage of the lower shoe-carrying portion of the shaft.

4. In a wear-testing apparatus of the character described, in combination, a frame, a support thereon for a test specimen, a wearer shoe for acting on a supported specimen, a shaft carrying said shoe at its end adjacent the specimen and mounted on the frame for rotary motion about its axis and also for longitudinal reciprocation, said shaft having a longitudinal through passage communicating at the shoe end with a through aperture in the shoe to carry off debris, a stationary bearing at the outer end of the shaft, and a cap at the outer end of said bearing and shaft, said cap having a central aperture, a tube mounted on said cap and extending into the shaft and communicating between the longitudinal passage therein and a debris-collecting vacuum system, said bearing cap and tube being constructed and arranged to provide a clearance chamber at the end of the shaft.

5. Wear-testing apparatus according to claim 4 wherein an air-entrance cleaner passage of relatively small diameter communicates between the clearance chamber and atmosphere.

6. In a wear-testing apparatus of the character described, in combination, a frame, a support thereon for a test specimen, a shoe for wearing a specimen on the support, a shaft carrying said shoe at one end, means to support the shaft for axial reciprocation and for rotation about its axis, a specimen-protecting plate element centrally apertured for passage of the shaft, said element having an area at least approximately that of the specimen to be tested, and fixed means on the frame for supporting the plate element stationarily above the test specimen and in such proximity thereto as to screen the latter from foreign matter, the plate element being of transparent material through which the specimen may be observed.

7. In a wear-testing apparatus of the character described, in combination, a frame, a support thereon for a test specimen, a shoe for wearing a specimen on the support, a shaft carrying said shoe at one end, means to support the shaft for axial reciprocation and for rotation about its axis, a specimen-protecting plate element centrally apertured for passage of the shaft, said element having an area at least approximately that of the specimen to be tested, and fixed means on the frame for supporting the plate element stationarily above the test specimen and in such proximity thereto as to screen the latter from foreign matter, the plate element comprising a plurality of mating sections supported for ready movement away from the shaft to afford access thereto and to the specimen support.

8. In a wear-testing apparatus according to claim 1, the construction wherein the shoe-supporting arm has operatively associated with it a longitudinally reciprocable rod, and means ac-

curately to control the extent of movement accorded the wearer shoe, comprising a stop member longitudinally adjustable on said rod and engageable with a fixed part to limit movement of the shoe toward the specimen.

9. Wear-testing apparatus according to claim 1, the construction wherein the shoe-supporting arm has operatively associated with it a longitudinally reciprocable rod, and means accurately to control the extent of movement accorded the wearer shoe, comprising a stop member longitudinally adjustable on said rod and engageable with a fixed part to limit movement of the shoe toward the specimen, and cooperating micrometer elements on the shoe-reciprocating rod, for variably positioning the stop member, including fine incremental settings thereof.

10. In a wear-testing apparatus of the character described, in combination, a frame, a movable platen thereon for a test specimen, means to move the platen, a wearer shoe mounted to have rotary motion in contact with a specimen on the moving platen, said interaction of the shoe and specimen tending to generate heat in the shoe, a motor and drive connections for the platen and for the shoe, a motor controlling switch, a circuit including a relay for actuating the switch, and a thermally responsive switch device associated with the shoe and included in said circuit, said switch device comprising a contact supported on a stationary part and a contact carried by a part moving with the shoe, said latter contact being subject to the heat condition of the shoe and being cooperable with the first contact to stop the motor at a predetermined temperature developed at the shoe.

11. Wear-testing apparatus according to claim 10 wherein the motor is operated on a power supply of normal or standard voltage, and transformer means is provided for operating the relay circuit containing the thermally responsive switch device upon a low voltage.

12. In a wear-testing apparatus of the character described, in combination, a frame, a movable platen thereon for a test specimen, means to move the platen, a wearer shoe mounted to have rotary motion in contact with a specimen on the moving platen, said interaction of the shoe and specimen tending to generate heat in the shoe, said shoe also being movable toward the specimen to wear it to increasing depths, a motor and drive connections for the platen and for the shoe, a motor controlling switch, a relay to operate said switch to stop the motor, said motor and its switch being in an operating circuit supplied with normal or standard voltage, relay-actuating circuits including transformer means supplying a relatively low voltage thereto, thermally responsive means in one relay-actuating circuit to cause the relay to throw out the motor switch at a predetermined temperature developed at the shoe, and relay-controlling contacts in another relay-actuating circuit similarly to operate the relay in response to wearing action of the shoe to a predetermined level of the test specimen.

13. In a wear-testing apparatus of the character described, in combination, a frame, a movable platen thereon for a test specimen, means to move the platen, a wearer shoe mounted to have rotary motion in contact with a specimen on the moving platen, said interaction of the shoe and specimen tending to generate heat in the shoe, a central through aperture in the shoe opening at its wearing face, a debris-collecting

vacuum system in closed communication with said aperture in the shoe, and one or more additional air passages extending inward from the periphery of the shoe wholly above its wearing face and communicating with said central aperture, for cooling purposes.

14. In a wear-testing apparatus of the character described, in combination, a frame, a movable platen thereon for a test specimen, means to move the platen, a wearer shoe mounted to have rotary motion in contact with a specimen on the moving platen, said interaction of the shoe and specimen tending to generate heat in the shoe, a central through aperture in the shoe opening at its wearing face, a debris-collecting vacuum system in closed communication with said aperture in the shoe, the wearer shoe including a shoe holder element, said element having a circulating chamber for a cooling fluid, inlet and outlet passages for said chamber, and flexible hose connections for said passages to admit and to carry off the circulating medium.

15. In a wear-testing apparatus of the character described, in combination, a frame, a movable platen thereon for a test specimen, means to move the platen, a wearer shoe mounted to have rotary motion in contact with a specimen on the moving platen, said interaction of the shoe and specimen tending to generate heat in the shoe, a central through aperture in the shoe opening at its wearing face, a debris-collecting vacuum system in closed communication with said aperture in the shoe, the shoe comprising a wearer element proper presenting a hard, smooth wearing surface having a mirror finish, and a shallow channel formation in said wearing surface communicating between the periphery thereof and the central through aperture in the shoe, for wear-contributing, air-cooling and debris-collecting purposes.

16. In a wear-testing apparatus according to claim 15, the construction wherein said communicating channel formation is comprised in shallow channel means in said wearing surface between the periphery thereof and the central shoe aperture and disposed and directionally arranged to subdivide the wearing surface into selected configurations to afford the desired rate of wear for a test specimen of a given character.

17. In a wear-testing apparatus according to

claim 4, the construction wherein the negative air pressure in the debris passage in the shaft and communicating with the through aperture in the wearer shoe is subject to intermittent variations with each engagement and disengagement of the shoe and test specimen, gauge means on the frame adapted to have operative communication with the main passage and including a movable member to indicate visually the degree of negative pressure, and valve means normally automatically shutting off the gauge from said communication thereby to avoid pulsating movement of the movable gauge member upon engagement and disengagement of the wearer shoe and test specimen.

18. In wear-testing mechanism according to claim 4, the combination therewith of adjustable venting means to determine the maximum negative pressure developed in the vacuum-system communicating longitudinal passage of the shoe-carrying shaft and at the communicating through aperture in the shoe during engagement of the shoe and test specimen.

19. Wear-testing apparatus for flexible sheet material, said apparatus comprising, in combination, a frame, a platen thereon for a test specimen, said platen mounted for movement in a given plane in various directions other than along a given straight line in such plane, drive means for so moving the platen, a wearing instrumentality for making pressing contact upon a specimen on said platen, said platen moving in different directions during such contact of the wearing instrumentality upon the specimen whereby the latter tends to be moved relatively to the platen in different directions in said given plane, and means having positive non-slip gripping engagement with lateral portions of the specimen and including holding parts laterally yieldable bodily relative to the platen while retaining said gripping engagement with the specimen, for tensioning the specimen flatwise on the platen yieldably in two directions at substantial angles to each other in said plane thereby to retain the specimen in operative position on the platen subject to said platen movement and to contact of the wearing instrumentality.
